UNITED STATES PATENT OFFICE.

JOHN ROBSON, OF WATERBURY, CONNECTICUT, ASSIGNOR TO UNIVERSAL ENGINEERING CORPORATION, OF MONTREAL, CANADA, A CORPORATION OF CANADA.

DRIVING MECHANISM.

Application filed May 3, 1923. Serial No. 636,351.

My present invention relates to driving mechanisms of the type comprising a power-driven pump, motor mechanism operated by the fluid or liquid propelled by such pump, and suitable connections through which the liquid flows from the pump to the motor mechanism, and then back from the latter to the pump. The features to which my present invention is directed relate especially to automatic mechanism for controlling the action of the pump so as to maintain a substantially constant pressure at the delivery port, and also to mechanism for controlling the operation of the motor mechanism, particularly when the latter comprises a plurality of motor units. This motor-controlling mechanism is preferably constructed both for manual and for automatic control.

Letters Patent of the United States granted to Harvey D. Williams on June 15, 1909, No. 925,148 and on November 19, 1912, No. 1,044,838. The shaft 15 of said pump is journaled in a suitable casing 16 and is driven by a suitable engine or prime mover (not shown). With said shaft rotates a barrel 17 made with longitudinal cylinders 18 in which are adapted to reciprocate pistons 19, the stroke of these pistons depending on the inclination of the box 20 on which is mounted to rotate the swashplate 21 engaging the ends of the piston rods 22. As the pistons reciprocate, they suck or force oil through cylinder ports 23 adapted to register alternately, as the barrel rotates, with the two ports 24, 25 of the casing 16, one of said ports being the pressure or delivery port, and the other the suction port; for instance, 24 may be the pressure port, and 25 the suction port.

The invention has been designed especially in view of the requirements of machinery for grinding timber for the production of pulp, where very heavy strains occur, and where it is customary to operate a battery of grinders simultaneously. It will be understood, however, that the invention is susceptible of use in other relations, particularly in cases where a plurality of driven devices are operated from a single prime mover.

Without restricting myself to the specific disclosure made in this application, I will now proceed to describe typical and satisfactory embodiments of my present invention with reference to the accompanying drawings, in which Fig. 1 is a diagrammatic plan view of one arrangement embodying said invention and illustrating a pump and three motors driven thereby; Fig. 2 is a longitudinal vertical section through the pump; Fig. 3 is a transverse vertical section of the pump; Fig. 4 is a detail vertical section showing a slightly different arrangement of certain parts; Fig. 5 is a horizontal section through one of the controlling mechanisms associated with the respective motors; Fig. 6 is a plan view similar to Fig. 1, but illustrating an arrangement in which the motors are assumed to be reversible, whereas in the arrangement shown in Figs. 1 and 5 they are supposed to always rotate in the same direction; and Fig. 7 is a horizontal section through one of the motor-controlling mechanisms for use in connection with reversible motors of the type shown in Fig. 6.

At 26 I have indicated in Figs. 1 and 6, motors operated by the liquid propelled by the pump. These motors are of the same type as the pump, at least I prefer them so, and the pipe 27 connected with the pressure port 80 of the pump delivers the liquid (oil) under pressure to the several motors, by way of intermediate mechanism to be described below, while the return pipe 28 connected with the suction port of the pump receives the liquid which has operated the motors, through certain connections likewise set forth below. Thus, in the preferred form of this construction, each motor comprises a casing having two ports, similar to the pump ports 24, 25, 90 one of such motor ports serving as an inlet, and the other as an outlet for the liquid flowing through the motor. This fluid operates pistons similar to the pump pistons, and causes the rotation of a barrel similar to the pump barrel, the motor barrel being secured to a shaft 29 which constitutes the drive shaft for the grinder or other machine (not shown) operated by such motor. Inasmuch as the motor construction is substantially the same as that of the pump, and inasmuch as both pumps and motors of this type are well-known in the art, I have deemed it unnecessary to show the internal construction of the motor. It will be understood, however, that (as generally the case in pump-motor combinations of this character), the motor boxes corresponding to the pump box 20 are preferably held at a fixed angle, while the inclination or angle of the pump box 20 is variable.

In Figs. 1, 2, 3, and 6, I have shown a pump of the general type disclosed, for instance, in

For the purpose of maintaining a constant pressure in the delivery side of the pump, I may employ the following mechanism: The box 20 is provided with a lateral projection or stub 30 (parallel to the shaft 15 when the swashplate 21 is perpendicular to the shaft 15) having a sliding fit in a perforated ball 31 movable in a spherically curved seat in a block 32 movable along stationary seat in block 32 movable along stationary 10 slideways 33. With the block 32 is connected a rod 34 extending to a piston 35 mounted to slide in a cylinder 36. At one end, said cylinder is connected, by a pipe 37, with the pressure port 24 of the pump, so that, whenever 15 the pump is delivering liquid, the delivery pressure will tend to move the piston 35 in one direction and to effect a corresponding adjustment in the inclination of the pump swashplate 21 and in the output of the pump, 20 it being understood that the output of the pump (per revolution of the barrel 17) depends on the inclination of said swashplate. A counteracting force tends to move the piston 35 in the opposite direction. As illustrated in Fig. 2, this opposing force is furnished by the weights 38 resting on a holder 39 secured to an extension 40 of the piston rod 34, and when this construction is employed, the piston rod must be vertical or at least upright. Another way of accomplishing the 30 same result is indicated in Fig. 4, where one end of the cylinder 36 is connected with the pipe 37 as before, while the other end of said cylinder is connected with a source of fluid 35 under pressure, for which purpose the pressure of the water mains might be utilized, or, as illustrated, a pipe 41 of the standpipe character might be employed, preferably in connection with an elevated tank 42 containing 40 oil or other liquid and furnishing sufficient pressure to act as a substitute for the weights 38 of Fig. 2. With the arrangement shown in Fig. 4, the piston 35 need not move up and down, but might be placed in any position. 45 In the form of my invention illustrated by Figs. 1 and 5, I have assumed that the motors 26 always rotate in the same direction, that is, one port of the motor casing is always the inlet for the oil under pressure coming 50 from the pump, and the other port of the motor casing is always the outlet for the oil which has operated such motor and is to be returned to the suction port of the pump. In this case, in the embodiment shown, the 55 outlet port of each motor is connected by a branch 43 with a pipe 44 leading to an expansion tank 45, preferably located at a sufficiently high level to insure the complete filling of the entire pipe system connected 60 with said tank. This tank is under atmospheric pressure, and is only partly filled, so as to provide room for the expansion of the oil as it heats up during the operation of the plant. Expansion tanks have been provided 65 hitherto in pump-motor combinations of this

general character, although not in the exact relation here disclosed. Any tank located at a proper level to provide the necessary head may be utilized for the function of the tank 42 of Fig. 4. The expansion tank is 70 connected with the return pipe 28. Thus the return path of the oil from the motors to the pump will be clear.

From the delivery pipe 27 of the pump branches 46 lead to ports 47 in valve casings 75 48, there being one such casing for each motor 26. In the position illustrated by Fig. 5, the port 47 communicates with an annular chamber or channel 49 located between the two ends or heads 50, 51 of a piston valve movable in said casing and connected with a rod 52. At 53, this rod is connected loosely with a lever 54. A fulcrum for said lever is formed at times by the pivotal connection 55 located at one end of said lever and linking 80 it to a rod 56 mounted to slide in a cylinder 57, together with a piston 58 secured to said rod 56. A spring 59 tends to push the piston 58 inward, until it engages the end wall of said cylinder 57 as shown. This end of the 85 cylinder is connected by a channel 60 with a port 61 of the valve casing 48, and also, by a duct or pipe 62, with the inlet port of the motor 26. In the position illustrated by Fig. 5, the head or piston 50 cuts off communication 90 between the ports 47 and 61. In this construction, the head 51 serves simply to balance the pressure on the valve, and other balancing means might be substituted; however, the construction shown has the advantage of simplicity, particularly as it enables the same kind of valve to be used both for the arrangement shown in Fig. 5 and for that of Fig. 7. The lever 54 has a pin-and-slot connection at 63 with a nut 64 in threaded engagement with a screw 65 the shank of which has an unthreaded portion turning, 100 but not sliding, in bearing 66.

The operation of this form of my invention is as follows: The pump, operating in 110 the well-known manner, sends a stream of fluid under pressure into the pipes 27 and 46. The weights 38 (Fig. 2), or the hydrostatic pressure used as an equivalent of such weights (Fig. 4), will be adjusted to correspond to the desired degree of pressure. From the delivery or pressure port 24 of the pump, a portion of the oil will pass through the pipe 37 into the cylinder 36, tending to move the piston 35 in the direction opposite 115 to that in which it is urged by the weights 38 or by the hydrostatic pressure. Thus, should the pressure in port 24 rise, the piston 35 will move up, and (since with the apparatus illustrated the stub 30 will never move upwardly 120 beyond the horizontal position shown) such upward movement of the piston 35 will decrease the angle which said stub forms with the horizontal, and will thus bring the swashplate 21 toward the vertical position, thus 125 130

reducing the output of the pump. Similarly, any fall in the pressure at the delivery port 24 will cause the piston 35 and the stub 30 to move down, and will therefore adjust the 5 inclination of the swashplate 21 in such a manner as to increase the output of the pump. Therefore, if the machinery driven by the 10 motors 26 should encounter a sudden strain, causing the pressure to rise abnormally, or should the flow of oil to the motors become throttled or obstructed for any reason, the 15 pump will become adjusted automatically to a lower output, or even, in an extreme case, to idle running (position of Fig. 2). Of course, the pump output will also be increased automatically under reverse conditions.

The pressure liquid from the pipes 46 will pass through the port 47 of each of the controlling mechanisms into the annular channel 49 of the valve member movable in the corresponding casing 48. Before the pump is caused to deliver oil under pressure into the circuit, the valve 50, 51 is preferably set so that the channel 49 will connect the port 47 25 with the port 61. For this purpose, the engineer or other operator will turn the hand-wheel 67 attached to the screw 65, and thus swing the lever 54 about the point 55 as a temporary fulcrum. The spring 59 is made 30 of sufficient strength to hold the piston 58 in the end position shown, under normal conditions, notwithstanding the presence of oil under pressure in the channel or duct 60. The oil under pressure passes from pipe 46 35 through port 47, channel 49, port 61, duct 60, and pipe 62 to the respective motor 26, operating the same in the well-known manner, whereupon the oil passes from the outlet of the motor through the pipes 43, 44 to the expansion tank 45, and then returns through 40 the pipe 28 to the suction port 25 of the pump. Should the load on the machinery driven by one of the motors 26 increase the pressure will increase correspondingly in the pipe 62 45 and duct 60, thus moving the piston 58 against the action of the spring 59. At this time, the point 63 is stationary, and forms a temporary fulcrum for the lever 54, which is thus moved in such a direction as to cause the 50 head 50 to throttle, and in extreme cases to close entirely, the port 61, thereby automatically reducing the speed of the corresponding motor 26, or stopping such motor altogether. There is thus provided an automatic check to 55 the rise of the oil pressure in the motor beyond a predetermined adjustable limit, and damage to the machinery and to the motor is thus prevented. It will be noted that this automatic motor-control does not interfere 60 with the hand control obtained by turning the screw 65, which sets the motor for the desired normal speed. Also, the manual adjustment or control may be effected at any time, whether the machine is operating or 65 standing still.

It will be noted by reference to Figs. 2 and 4 that the weights 38 or the hydrostatic pressure will tend to bring the tilting box 20 to its extreme inclination when the pump is not working, so that with the pump at rest, the 70 stub 30 would be in its lowermost position. Evidently, it is undesirable to start the pump in this position, but for good starting, the box 20 should be in the neutral position shown in Fig. 2. I have therefore provided a simple 75 device for bringing the tilting box to said position before starting the pump. This device as shown in Fig. 2, consists of a screw 68 extending upwardly through the bottom of the pump casing 16 and adapted to engage the 80 slide block 32 from below, thus enabling it to be raised to the position shown. The pump having been started in this position, the screw 68 is lowered gradually, so that the inclination of the tilting box will increase under the 85 action of the weights 38 or of the hydrostatic pressure, until such action is counterbalanced by the pressure of the oil coming into the cylinder 36 through the pipe 37.

As an additional safeguard, I consider it 90 desirable to provide a by-pass between the pressure port 24 and the suction port 25 of the pump. This by-pass 69 is shown in Fig. 3, together with a manually-controlled valve 70 which is closed during the normal operation of the plant, but is opened when starting the pump. The starting of the pump is thus facilitated, particularly if the stub 30 should not have been brought to an exactly horizontal or neutral position, and damage to the 95 pump is prevented, especially in the case of the operator's neglecting or forgetting to adjust the screw 68 to the position shown in Fig. 2, before starting the pump.

In Figs. 1 and 5, the motors 26 are supposed to always rotate in the same direction. Where it is desired to have the motors to rotate in one direction or the other, that is, where the motors are reversible, I may adopt the arrangement shown in Figs. 6 and 7. The 100 parts 46, 47, 49, 50, 51, 52, 53, 54, 55, 56, and 61 to 67 inclusive are the same as in Figs. 1 and 5. The pipe 44, instead of being always connected with the same port of the motors, is connected with both ports, since either 105 motor port may be the inlet or the outlet, when the motor is reversible. Pipes 43' connect the pipe 44 with one of the motor ports, and pipes 43'' with the other motor ports, through the intermediate or controlling 110 mechanism shown in Fig. 7. Said pipes 43', 43'' lead to ports of the valve casing 48' which are located on opposite sides of the port 47 which supplies oil under pressure 115 (from the pump). In the neutral position 120 illustrated, the channel 49 communicates only with the pressure pipe 46. In operation, however, the channel 49 communicates either with both ports 47 and 61 (at which time 125 communication between port 61 and pipe 43'' 130

is cut off), or with the two ports 47 and 71 (at which time communication would be cut off between port 71 and pipe 43'). When port 47 communicates with port 61 or 71 respectively, there is established simultaneously communication between port 71 and pipe 43', or between port 61 and pipe 43'', respectively. In this form of my invention, therefore, the head 51 serves not only to make the 10 valve balanced as to pressure, but controls the connection of port 71 with port 47 and with pipe 43' respectively, the head 50 performing corresponding functions relatively to the ports 47, 61 and to the pipe 43''. Port 15 61 leads into channel 60' which by means of pipe 62 communicates with one of the ports of motor 26. Port 71 leads to a duct 72 which by means of pipe 73 communicates with the other port of said motor 26. The 20 channels or ducts 60' and 72 connect with opposite ends of cylinder 57', so as to lead the pressure oil to opposite faces of the piston 58' secured to the piston rod 56. In order to hold the piston 58' in the central position 25 shown, when it is not exposed to the pressure of the oil, I may employ a spring 59' contained in a chamber or casing 74 and coiled around an extension 56' of the piston rod 56. The ends of said spring bear against plates 30 or abutments 75, 76 movable lengthwise of said rod, and located between a collar 56'' on the rod extension 56', and a nut 77 on the end of said extension. The spring thus tends to keep said abutments in contact with the 35 collar 56'' and with the nut 77 respectively.

By a proper manipulation of the handwheel 67 of Figs. 6 and 7, the operator can shift the valve so that port 47 will communicate with either the port 61 or the port 71, and this 40 simultaneously keeps connected, either port 71 with pipe 43', or port 61 with pipe 43'', respectively. According as the adjustment is made to effect one of these connections or the other, the motor will be driven in one direction or the other by the oil under pressure 45 coming from the pump through pipe 46. As will be seen readily, this oil will pass from pipe 46 through port 47 and channel 49 either to port 61 or port 71, according to the position of the valve 50, 51, and will then reach one port of the motor either through duct 60' and pipe 62, or through duct 72 and pipe 73, respectively. In the event of a rise of 50 pressure, the piston 58' will be moved in such a direction as to reduce the speed of the motor (without changing the direction in which the motor rotates). For instance, if the pressure oil is flowing to the motor through channel 60' and pipe 62, a rise in pressure will 55 force the piston 58' toward that end of cylinder 57' which is connected with duct 72; the abutment 76, being in engagement with the nut 77, will move in unison with the piston 58', but the abutment 75, being in engagement 60 with the end of the cylinder 57', will remain

stationary, so that the spring 59' will be compressed. At the same time, in substantially the same manner as described with reference to Figs. 1 and 5, the lever 54 will be swung on the point 63 as a temporary fulcrum, moving 70 the valve 50, 51 in the same direction as the piston 58', toward the neutral position shown in Fig. 7, thus throttling or closing the communication between the ports 47 and 61. (It will be understood that when the pressure 75 oil is flowing to the motor through the pipe 62, the valve 50, 51 is shifted toward the port 61, from the neutral position illustrated.) On the other hand, should the pressure oil be flowing to the motor through the pipe 73, a 80 rise in pressure will move the piston 58' toward that end of cylinder 57' which is connected with duct 60'. In this case, the abutment 76 will remain stationary, since it engages a projection on the casing 74, and the 85 abutment 75 will move outwardly with the piston, thus compressing the spring 59', this spring, when compressed in either way, tending to restore the piston to the former position as soon as abnormal conditions cease. 90 The valve 50, 51 will again be moved in the same direction as the piston 58', thus first throttling the stream of oil at the port 71, and then closing said port entirely, if the movement is of sufficient extent; the movement 95 may even reach the limit of the neutral position illustrated, in which the port 71 is again open, but communicates with the pipe 43'. Here, too, the velocity of rotation of the motor will be reduced automatically when the 100 pressure rises, without however changing the direction in which the motor rotates. The oil leaving the motor through one of its ports passes back to the pipe 44, either through 62, 60', 61, 43'', or through 73, 72, 71, 43', according to the direction in which the motor is 105 rotating. It will be understood that by means of the handwheel 67, the operator can adjust the normal speed of each motor, whether the same be running or not, as in the 110 form of my invention first described; furthermore, in the construction illustrated by Figs. 6 and 7, manipulation of the handwheel 67 will also enable the operator to reverse the motors, or any one of them individually, 115 while the pump is propelling the oil out through the same delivery port, that is, without reversing the functions of the pump ports.

It will be understood that the means for facilitating starting of the pump, described with reference to Figs. 2 and 3, are applicable to the form of my invention shown in Figs. 6 and 7, as well as to the form first described.

I claim as my invention:

1. A driving mechanism, comprising a 125 pump, a plurality of motors actuated by the fluid propelled by such pump, independent controlling mechanisms, associated with the respective motors, each of said mechanisms including a manually adjustable valve and a 130

- fluid pressure responsive member connected with said valve and interposed between the pump and motor for governing automatically the amount of fluid admitted to its respective motor as the load on the motor varies, and additional mechanism controlling the output of the pump automatically in accordance with the resistance such fluid encounters in its path.
- 5 2. In a driving mechanism, a pump, a plurality of motors actuated by the fluid propelled by said pump, a balanced valve interposed in the path of the fluid from the pump to each of the motors, means under the control of the operator, for manually adjusting each of such valves individually, a piston exposed to the pressure of the fluid flowing from the pump to the respective motors, and means, operated by the movement of said piston, for shifting said valve automatically without altering the manual adjustment thereof.
- 10 3. In a driving mechanism, a pump, a plurality of reversible motors actuated by the fluid propelled by said pump, each motor having two ports either of which may serve as an inlet for the fluid coming from the pump, a valve interposed in the connection from the pump to each of the motors and controlling the flow of the fluid to one port of the motor or the other, and also controlling the cross section of the fluid current and thereby the speed of the respective motors, means under the control of the operator for manually adjusting said valve, a piston, a cylinder in which said piston is movable, connections from opposite ends of said cylinder to opposite ports of the respective motors, and a connection from said piston to the respective valve to operate the latter automatically in response to variations in the pressure of the fluid passing to the respective motors without altering the manual adjustment of said valve.
- 15 4. In a driving mechanism, a pump, a plurality of reversible motors actuated by the fluid propelled by said pump, each motor having two ports either of which may serve as an inlet for the fluid coming from the pump, independent valves each interposed in the connection from the pump to the respective individual motor, and controlling the flow of fluid to one port of each motor or the other port thereof, and also adapted to throttle the fluid current and thereby vary the speed of the respective motor, manually operable means under the control of the operator, for shifting said valve to alter the speed of the motor or to reverse such motor, and fluid pressure actuated means for each valve, interposed between said pump and each motor, and connected with its respective valve to actuate said valve automatically for altering the speed of the motor without reversing it or altering the manual adjustment of said valve.
- 20 5. In a driving mechanism, a pump, a reversible motor actuated by the fluid propelled by said pump and having two ports either of which may serve as the inlet for the fluid coming from the pump, a device, under the control of the operator, for changing the speed of the motor or reversing its rotation, by governing the admission of driving fluid to the motor, and automatic means, responsive to variations in fluid pressure, associated with said motor-controlling device, for altering the speed of the motor without reversing it.
- 25 6. In a driving mechanism, a pump, a reversible motor actuated by the fluid propelled by said pump and having two ports either of which may serve as the inlet for the fluid coming from the pump, and a device including a manually operable valve, under the control of the operator, for directing the fluid from the pump to one motor port or the other and varying the fluid current and a fluid pressure responsive member connected with said valve for automatically operating it to vary the speed of said motor in accordance with variations in the pressure of the fluid passing to said motor.
- 30 7. In a driving mechanism, a pump of variable output, a reversible motor actuated by the fluid propelled by said pump, and having two ports either one of which may serve as the inlet for the fluid coming from the pump, a motor-controlling device including a manually operable valve for directing the fluid from the pump to one motor port or the other and varying the fluid current and fluid pressure responsive means connected with said valve for automatically operating it to vary the speed of said motor in accordance with variations in the pressure of the fluid passing to said motor, and an independent automatic pressure-responsive device for varying the output of the pump.
- 35 8. In a driving mechanism, a pump, a motor actuated by the fluid propelled by said pump, pipe lines connecting said pump and motor, a controlling device interposed in said pipe lines between said pump and motor, said device including a valve, a manually operable means to set said valve in adjusted position, and fluid pressure operated means connected with said valve for automatically controlling the admission of driving fluid to said motor without varying the setting of said valve.
- 40 9. In testimony whereof I have signed this specification.

JOHN ROBSON.
